UNITED STATES PATENT OFFICE.

JUSTIN KAY TOLES, OF CHICAGO, ILLINOIS, ASSIGNOR TO BAUER & BLACK, OF CHICAGO, ILLINOIS, A CORPORATION OF ILLINOIS.

MACHINE FOR MAKING PLASTER OF PARIS BANDAGES.

No. 836,414.

Specification of Letters Patent.

Patented Nov. 20, 1906.

Application filed August 11, 1902. Serial No. 119,256.

To all whom it may concern:

Be it known that I, JUSTIN KAY TOLES, a citizen of the United States, residing at Chicago, in the county of Cook and State of Illinois, have invented certain new and useful Improvements in Machines for Making Plaster Paris Bandages, of which the following is a specification.

This invention relates to novel improvements in machines for making plaster-paris bandages; and its object is to provide a simple and inexpensive machine which can be easily operated for making plaster-paris and other bandages of a like character which involve applying pulverulent plaster-paris or similar product on a web.

Another object of the invention is to thoroughly incorporate the plaster material in the fabric backing or foundation and spread the material in a smooth and even layer to provide a bandage of uniform character throughout its length, and a further object of the invention is to provide for winding the bandage in rolls of predetermined length and automatically stop the machine when the roll has been completely wound.

Another important object of the invention is to produce a roll which will at once become thoroughly and completely saturated when the roll is submerged in water by winding the bandage comparatively loosely at the center and comparatively tightly at the outer part of the roll.

Another important object of the invention is to provide for depositing powdered alum on the web to commingle with the plaster-paris to absorb any moisture which may be present, and thereby keep the plaster in a perfectly dry condition for an indefinite period and ready for instant use; and still another important object of the invention is to provide for depositing powdered alum on the web to commingle with the plaster-paris to hasten the set and increase the tensile strength of the bandage when applied.

With these and other ends in view I have illustrated one manner in which the machine may be embodied in the accompanying drawings, referring to which—

Figure 1 is a front view of a machine embodying my invention. Fig. 2 is a side elevation of the machine, parts of the frame being broken away to show the operating mechanism. Fig. 3 is a vertical sectional view.

Fig. 4 is a sectional view on the line 4-4 of Fig. 3. Fig. 5 is a sectional view on the line 5-5 of Fig. 3. Fig. 6 is a sectional view on the line 6-6 of Fig. 4.

Referring to the drawings, in which like numerals of reference indicate corresponding parts in the several figures, 10 designates the main drive-shaft, which is provided with a loose belt-pulley 11 and is journaled in bearings in a frame of suitable construction, which is designated generally by 12. The belt-pulley is made tight with the main shaft by means of a clutch of suitable construction operated by a lever 13, Fig. 2, which is conveniently arranged at the front of the machine and works on a guide 60. In the drawings I have shown a movable disk 14, keyed to the shaft 10 and provided with studs 15, adapted to enter holes in the disk 16, rigid with the pulley 11, so that when the lever is thrown the disk 14 will be carried forward and the studs thereon will enter the holes in the disk 16 to lock together the pulley, the sliding disk, and the shaft, Fig. 5.

A drum 17 is mounted on a shaft 18, journaled in the frame, and this drum is operated by means of an internal gear 19, which meshes with a pinion 20 on the main shaft, Fig. 5. The drum is provided with a covering 21, of carpet or other suitable material, which will serve to hold the web 22 and make the drum feed the web forward beneath the spout 23 of the hopper 24. The web is preferably wound on spools 25 and mounted on a shaft 26, journaled in bearings in the brackets 27 on the frame, and the web is carried from the spool, preferably over one or more tension-rollers, and over the feed-drum to the winding-spindle, as indicated in Fig. 3. The hopper and its spout are of any suitable construction, and an agitator 28 is preferably arranged in the hopper and operated by a belt 29, running on the pulley 30 on the agitator-shaft 31 and on the pulley 32 on the drum-shaft 18. The spout is provided with a glass front 33 in one part thereof; so that the operator can observe when the supply of material is becoming exhausted. The hopper-spout has its discharge end shaped to conform substantially to the periphery of the drum, and it discharges the material on the web while the latter is being carried by the drum across the discharge-opening.

A gate 34 is pivotally mounted on a bracket-arm 35,

fastened to the spout, and this gate is normally held by a spring 36 to bear upon the web at the point where it emerges from below the discharge-opening in the spout. This 5 gate operates not only as a tension device for the web, but also as a scraper to remove surplus material deposited on the web and to spread the material evenly over the web.

For the purpose of cleaning the covering 10 on the drum and to prevent it becoming clogged with the plaster material I provide a revolving brush 37, Fig. 5, which is carried by a shaft 38 and operated from the drum-shaft by means of the gears 39 40 and the intermediate idle gear 41, so that the brush will 15 turn in the same direction as the drum turns, but in an opposite direction at their meeting edges, and keep the surface of the covering of the drum free from plaster.

20 The bandage is bound in rolls on a spindle 42, to which it is clamped by means of a spring-clamp 43. In fastening the web to the spindle the clamp 43, Fig. 6, is arranged in the socket 44 of the movable support 45, 25 and this support is caused to carry the clamp upward with the web thereon and fasten it securely to the spindle. A toggle 46 is connected to each end of the support and to the frame at 47, and cords 48 are fastened to the 30 toggle and run over the pulleys 49 and are connected to a pedal-lever 50. The weight of the support is sufficient to carry it to its normal lowered position, or a spring may be connected with the pedal-lever for this purpose, and it will be readily observed that 35 when the pedal-lever is depressed the cords will be drawn to operate the toggles and throw the support upward and force the clamp upon the spindle with the web tightly 40 held between them.

The spindle is journaled in suitable bearings in the frame and is driven by means of a pinion 51, which meshes with an idle pinion 52, Fig. 4, and this latter pinion is operated 45 by means of a sprocket-chain 53, traveling on a sprocket-wheel 54 on the main shaft and on a sprocket-wheel 55, connected with the pinion 52. The spindle is adapted to be disconnected from the bandage-rolls and the 50 clamp by simply withdrawing it at the side of the machine, the clamp bearing at that time against the socket-plate 56 in the frame, and in order to connect the spindle with the driving-pinion 51 I provide a clutch 55 device of suitable construction, which in the drawings I have shown to consist of a friction-disk 57, rigid with the spindle, and a corresponding disk 58, rigid with the pinion 51, these disks being each provided with a 60 fiber facing of suitable material to provide sufficient frictional engagement surfaces.

In order to regulate the speed at which the spindle revolves and thereby control the winding of the bandages, I provide a hand-lever 59, which is bifurcated or otherwise

constructed in a suitable manner to engage the boss 62 on the disk 57, so that this disk may be clamped tightly with the disk 58 to revolve coincidently therewith, or the pressure may be reduced by operating the hand-lever to decrease the friction and permit the spindle to travel at a lower rate of speed than the driving-pinion. I prefer to wind the bandage-rolls loosely at the center and comparatively tightly at the outer part thereof, 70 and it will be readily understood that this can be easily accomplished by manipulating the hand-lever, and thereby regulating the speed of travel of the spindle. This hand-lever is normally under tension of a spring 63, 75 which tends to keep the clutch open.

I provide a knife 64 for severing the web after the roll has been wound, and this knife is pivoted to the frame at 65 and is operated by means of a lever 66, connected with the 80 heel of the knife by a link 67, Fig. 1.

For the purpose of regulating the length of bandage in a roll I provide a disk 68 on the brush-shaft 38 and arranged to engage the lower end of the lever 69, to the upper end of 90 which the hand-lever 13 is connected and by means of which the clutch on the main shaft is operated. The disk is provided with a slot 70, in which the lower end of the lever 69 is adapted to seat itself after a bandage of 95 the proper length has been wound in a roll on the spindle. If it is desired to wind bandages of a length of five yards, the parts may be constructed and proportioned so that the brush-shaft will revolve once to five revolutions of the drum-shaft, or at least until a roll of the required length has been wound on the spindle. In its normal position the lower end of the lever 69 is seated in the slot 70, as 100 shown in Fig. 5, and when the hand-lever is 105 operated to throw the clutch and start the machine the lower end of the lever 69 will be carried out of the slot and will ride against the peripheral edge of the disk, being held in this position by means of the spring 71, Fig. 110 2, until the disk has made a complete revolution, when the lower end of the lever will again be carried by the spring into the slot 70 and the clutch opened and the machine stopped.

With a machine constructed in accordance with my invention, as hereinbefore described, I am able to apply the plaster to the web evenly and expeditiously and wind a number of rolls of the same or different widths simultaneously, and the bandages will all be of uniform length. The web is held at tension in passing around the drum, and as it is generally a loosely-woven fabric the fiber of the carpet will operate to some extent to spread the fibers of the web, so that the plaster will penetrate the web and cling thereto. The plaster is spread upon the web evenly and smoothly by means of the gate 34, and this gate also holds the web at tension between 115 120 125 130

the discharge-spout of the hopper and the spindle, so that the web will not vibrate and loosen or throw off the plaster. I provide a chute 72, through which the plaster that is 5 brushed off of the drum, as well as any that may come from the web, may fall into a receptacle 73. The means for regulating the speed at which the spindle travels is of 10 special importance, as it enables the operator to start the spindle rotating at a low rate of speed, and thus wind the web loosely at first, the hand-lever being operated gradually to increase the speed of the spindle, and thereby cause the web to be wound more 15 tightly as the roll gets larger.

In connection with the machine as heretofore described I may use the following mechanism for depositing powdered alum on the web before the plaster is applied thereto: 20 This mechanism comprises a hopper 74, Fig. 3, between the feed-drum and the supply-spool, and the web is carried from the supply-spool around a roller 75 at the lower discharge end of the hopper and around a roller 25 76, across or partly across the top of the hopper, and around a roller 77, from whence it passes to the drum and preferably against a tension-roller 78. The roller 75 operates as 30 a feed-roller to carry the powdered alum from the hopper to the web, and in order to regulate the supply of alum thus carried by the feed-roll I provide a scraper 79, which is fastened to the hopper and operates, in conjunction with the feed-roll, to permit only a 35 predetermined quantity of the alum to be applied to the web. As a further precaution against the web carrying off too much alum, I preferably cause the web to travel across the open top of the hopper in the manner 40 previously described and then provide means for vibrating the web between the rollers 76 and 77 to loosen and discharge any surplus alum that may be carried thereby. This 45 vibrator may be constructed in many different shapes; but in the drawings I have shown a simple form comprising a shaft 80, carrying flexible arms 81, made of leather or other suitable material and arranged to strike the web, the shaft being driven by a belt 82, 50 traveling on the pulley 83, and a pulley 84 on the brush-shaft, Fig. 5. The alum which is thus applied in small quantity to the web before the plaster is applied will absorb all moisture in the fabric and whatever moisture 55 may be taken up by the fabric from the atmosphere, and thus the plaster is entirely freed from moisture as it is made, and it will be preserved indefinitely; so that it will always be in perfect condition for immediate 60 use. Of course the alum-applying mechanism may be dispensed with, if desired; but I prefer to use it in connection with the other parts of the machine in the manner shown and described.

I have described the machine as utilized 65 for making plaster-paris bandages; but I do not limit myself to this particular use, as it may be adapted and used for other purposes and with equally satisfactory results; nor do I limit myself to the particular construction 70 and arrangement of parts shown and described, as these may be varied and changed to suit different conditions without departing from the spirit or sacrificing the advantages of the invention. 75

Having thus fully described my invention, what I claim, and desire to secure by Letters Patent, is—

1. The combination of a hopper, a discharge-spout therefor, and a drum covered 80 with fibrous material and operating beneath the discharge end of the spout and feeding a web on which the material is deposited from the spout.

2. The combination of a hopper, a discharge-spout therefor, means for holding the web at tension, and a drum covered with fibrous material for spreading the fibers of the web and feeding it across the discharge end of the spout to receive the material to be 90 deposited thereon.

3. The combination of a hopper, a discharge-spout therefor, a drum for carrying a web across the discharge end of the spout to receive the material to be deposited thereon, 95 and a device pivoted on the front of the discharge-spout and engaging the web as it leaves the drum for removing surplus material from the web.

4. The combination of a hopper, a discharge-spout therefor, means for carrying a web across the discharge end of the spout to receive the material to be deposited thereon, and a device operating at tension on the web to remove surplus material therefrom. 100

5. The combination of a hopper, a discharge-spout therefor, means for carrying a web across the discharge end of the spout to receive the material to be deposited thereon, and a pivotally-mounted device operating on 110 the web to remove surplus material therefrom.

6. The combination of a hopper, a discharge-spout therefor, means for carrying a web across the discharge end of the spout to receive the material to be deposited thereon, 115 and a pivotally-mounted and spring-controlled device operating on the web to remove surplus material therefrom and hold the web at tension.

7. The combination with means for depositing material on a web, of a drum for feeding the web, said drum being provided with a fibrous covering. 120

8. The combination with means for depositing material on a web, of a drum for feeding the web, said drum being covered with carpet. 125

9. The combination with means for depos-

iting material on a web, of a drum provided with a fibrous covering for feeding the web, and a brush for cleaning the said covering.

10. The combination with means for depositing material on a web, of a drum for feeding the web, and a brush for cleaning the surface of the drum and revolving in the same direction as the drum but with their contacting faces moving in opposite directions.

11. The combination of a main shaft, a drum for feeding a web, an internal gear on the drum, a pinion on the main shaft meshing with said internal gear, a brush located below the drum for cleaning the surface of the drum, and means for operating the brush-shaft from the drum-shaft.

12. The combination of a drum for feeding a web and means for revolving the drum, a clutch for throwing the drum into and out of operation, a lever connected with the clutch, and a revolving disk operating on said lever to open the clutch after the disk has completed a revolution.

13. The combination of a drum for feeding a web and means for revolving the drum, a clutch for throwing the drum into and out of operation, a lever connected with the clutch, a revolving disk provided with a slot to receive the lower end of the lever, and a spring for throwing the lever into the slot after the disk has completed a revolution.

14. The combination with means for feeding a web and depositing material thereon, of a spindle on which the web is to be wound, means for operating the machine, and means for automatically stopping the machine after a predetermined length of web has been wound on the spindle.

15. The combination with means for feeding a web and depositing material thereon, of a spindle on which the web is to be wound, means for revolving the spindle, and means for controlling the speed of travel of the spindle.

16. The combination with means for feeding a web and depositing material thereon, of a spindle on which the web is to be wound, means for revolving the spindle, a clutch, and a lever for operating the clutch to control the speed of travel of the spindle.

17. The combination of a hopper and means for feeding a web around the discharge end thereof, means for depositing material from the hopper on the web, and means located above the hopper for vibrating the web to discharge surplus material thereon into the hopper.

18. The combination of means for deposit-

ing powdered alum on a web, means for depositing powdered plaster-paris on the web after the alum has been deposited thereon, and a drum covered with fibrous material and carrying the web beneath said plaster-paris-depositing means and spreading the fibers of the web to receive the plaster-paris.

19. The combination of means for feeding a web, means for depositing alum thereon, means for removing surplus quantity of alum from the web, means for depositing plaster-paris on the web after the alum has been deposited thereon, and means for spreading the plaster-paris evenly on the web and removing surplus plaster.

20. The combination of a fibrous-covered roller for feeding a web, a brush for cleaning said roller, means for depositing alum on the web before it passes over the roller, and means for depositing plaster on the web as it is carried by the roller.

21. In a plaster-paris-bandage machine, the combination of a spindle on which the bandage is to be wound, and a spring-clamp for securing the bandage to the spindle.

22. In a plaster-paris-bandage machine, the combination of an endwise-removable spindle on which the bandage is to be wound, and a clamp for securing the bandage to the spindle and support the bandage-rolls when the spindle is removed.

23. In a plaster-paris-bandage machine, the combination of a spindle on which the bandage is to be wound, a clamp for securing the bandage to the spindle, and a vertically-movable support for carrying the clamp with the bandage thereon into engagement with the spindle.

24. In a plaster-paris-bandage machine, the combination of a spindle on which the bandage is to be wound, a clamp for securing the bandage to the spindle, and a vertically-movable support provided with a socket to receive the clamp and adapted to carry the clamp with the bandage thereon into engagement with the spindle.

25. In a plaster-paris-bandage machine, the combination of a spindle on which the bandage is to be wound, a clamp for securing the bandage to the spindle, a support provided with a socket to receive the clamp, and a toggle mechanism for moving said support vertically to engage the clamp with the bandage thereon with the spindle.

JUSTIN KAY TOLES.
